GRINDING MACHINE

Application filed August 6, 1931. Serial No. 555,576.

This invention relates to improvements in grinding machines and especially to improvements in an automatic grinder.

An object of the invention is the provision of an improved automatic grinding machine for grinding the exterior surfaces of work pieces concentric to the bore or axis thereof.

Another object of the invention is the provision of an external grinding machine automatically operated and adapted to be loaded automatically from a hopper or like mechanism.

A further object of the invention is the provision of a grinding machine in which the loading time is reduced to a minimum and the productive hours increased to a maximum.

Another object of the invention is the provision of an improved external grinder for grinding cylindrical work pieces and utilizing an improved work driving mechanism which automatically engages and rotates the work without the use of dogs, or the like.

Other objects and advantages of the present invention should be readily apparent by reference to the following specification considered in conjunction with the accompanying drawings and it is to be understood that any modifications may be made in the exact structural details there shown and described, within the scope of the appended claims, without departing from or exceeding the spirit of the invention.

In the drawings:

Figure 1 is an elevational view of a grinding machine embodying the improvements of this invention.

Figure 2 is a top plain view of the machine shown in Figure 1.

Figure 3 is an elevational view through the throat of the grinding machine, certain parts being shown in cross section.

Figure 4 is a view similar to Figure 3 but in section and taken on line 4—4 of Figure 2.

Figure 5 is a sectional view on line 5—5 of Figure 3.

Figure 6 is a view taken on line 6—6 of Figure 3, certain parts being shown in elevation and others in section.

Figure 7 is a sectional view taken from line 7—7 of Figure 2.

Figure 8 is a sectional view taken on line 8—8 of Figure 7.

Figure 9 is a sectional view on line 9—9 of Figure 8.

Figure 10 is a fragmentary sectional view taken on line 10—10 of Figure 8.

Figure 11 is a sectional view longitudinally of the machine through the friction drive wheel as used in this machine and forming a detail of the invention.

Throughout the several views of the drawings similar reference characters are employed to denote the same or similar parts.

A machine embodying this invention may comprise a base or bed 15 having rising therefrom at one end thereof a pedestal bearing 16 for a spindle 17 to which is secured the grinding wheel 18 for rotation in a clockwise direction at a high grinding rate of speed. The bed 15 is further formed on its upper surface with a guideway 19 for a slide 20 mounted thereon and shiftable longitudinally of the bed. Superimposed on the slide 20 is a second slide 21 carrying head 22 in which is journaled a spindle 23 for a wheel 24 hereafter referred to as the friction drive wheel. The proximate points of the grinding wheel 18 and friction drive wheel 24 are spaced from one another a distance corresponding to the final size of the work.

The slides 20 and 21 are adapted to be shifted relative to one another when setting-up the machine for operation on a given size of work or they are adapted to be shifted as a unit relative to the bed 15 for effecting a relative feed between the work and grinding wheel. For this purpose there is provided an adjusting screw 25 having its threaded end received in a nut 26 mounted in the rear wall of the upper slide 21. The screw 25 is rotatably journaled in a housing 27 and extends therebeyond to which is secured a pilot or hand wheel 28. In order that the upper slide 21 may be moved relative to the lower slide 20, clamps 29 are provided for fastening the said lower slide to the bed 15 while to permit the slides to move as a unit, the clamp 30 is resorted to.

65

75

95

100

The lower slide 20 is provided at its inner end with a block 31 which subtends the grinding throat and bears the work supporting members. As seen in Figures 3 and 4, the 5 block 31 is provided with a rotatable turret head 32 having a plurality of work spindles 33 projecting therefrom. The spindles 33 are mounted in antifriction bearings 34 secured in suitable bores in the head 32. Each spin- 10 dle is provided with a tapered nose 35 for entering the bore in the work 36. The spindles 33, adjacent the tapered nose 35, are provided with a plane bearing portion 37 which fits the bore of the work at that end.

15 The turret head 32 is secured to a shaft 38 journaled at opposite ends in uprights 39 and 40 which are secured to and extend upwardly from the block 31. The turret 32 has a loading station and an operating station at points 20 diametrically opposite one another. Opposed to the center in the operating station is a tailstock center 41 which is similar to the centers or spindles 33 and has a tapered nose 42 and a bearing surface 43 for the work.

25 The inner end of the center or spindle 41 is mounted on antifriction bearings 44 carried by the sliding sleeve 45. The sleeve 45 is slidably actuated through a suitable bore formed in a tailstock or support 46. This sup- 30 port 46 is mounted on the bracket or block 31 of the lower slide. A key 47 is carried by the bracket 31 and received in a keyway 48 in the support 46, to insure alignment of the spindle 41 with the turret spindles 33.

35 The tailstock or support 46 may be ad- 35 justed longitudinally of the bracket 31 to- 40 ward and from the turret 32 by means of a screw 49 rotatably journaled in a lug 50 of bracket 51 secured as by cap screws 52 to the 45 said block or bracket 31. This adjustment of the support 46 enables the grinding of work pieces of different lengths. The sup- 50 port or tailstock 46 is provided on opposite sides with a longitudinal flange 155 having 55 elongated perforations 156 therein through which clamp bolts 157 extend into the block or bracket 31 for clamping the support or tailstock 46 in adjusted positions.

In order to insure the proper positioning of 55 the work pieces 36 on the spindles 33 and to insure the work contacting with the stop shoulder 158 on each spindle, there is provided a guard or positioning band 159. As seen in Figure 3, the free end of the guard 159 60 is flared as at 160, so that should a work piece or pieces extend beyond the proper point they will be forced onto the spindles by the camming action of the said flared end 160. The guard is held in place by a bracket 161 65 secured to the support or tailstock 46, as well as by brackets 162 and 163 respectively carried by the upright 40 and block or bracket 31. The guard 159 has a perforation 164 therein through which the center or spindle 65 projects. This perforation is somewhat

larger than the diameter of the spindle but is of a diameter less than that of the adjacent end of the work. Therefore, if the work tends to stick to the spindle 41 as it is being retracted the guard surrounding the perforation acts to strip the work from the center. 70

The bracket 31 is further provided at opposite ends on one of its vertical faces with bearing lugs 53 and 54 in which is slidably 75 mounted a rod 55. The rod 55 carries near its rear end the cam 56 having an inclined cam face 57. The rod 55 carries near its other end the upstanding post 58 having an elongated perforation 59 therein receiving a pin 60 from the lever 61. The cam face 57 on the cam block 56 is adapted to engage and oscillate a lever 62 which is fast on a shaft 63 extending transversely through the tailstock or support 46. Also, secured to the shaft 63 for movement therewith is an arm 64 which has its upper end bifurcated, as at 65, to receive a pin 66 extending from the sliding sleeve 45 through an elongated perforation 67 formed in the support 46. The lever 61 is rotatably journaled on the shaft 63 and lies against the outer face of the upright 40. Pivoted at 68 to the lever 61 is a pawl 69 actuated by spring 70 toward the ratchet 71 secured by cap screws or the like 72 to the end 80 of the shaft 63.

The rod 55 is adapted to be actuated to the left, as seen in Figure 3, for indexing the turret head 32 to place an unfinished work piece in the throat of the grinder. The operation of these parts is as follows: Movement 85 of the rod 55 to the left first effects an engagement between the cam face 57 and the arm 62 which actuates said arm in a clockwise direction about the axis of the shaft 63. This effects a retraction of the spindle 41 from the work 36. Continued movement of the rod 55 to the left eventually takes up the lost motion between the nose 73 of the pawl 69 and the next tooth 74 of the ratchet 71. At this time the ratchet is advanced 45° to the next 90 station whereupon the rod 55 is actuated to the right. A locking mechanism, subsequently to be described, locks the turret in such adjusted position so that the said movement of the rod 55 to the right causes the pawl 69 to ride on top of the teeth of the ratchet 71. Also, as the cam block 56 backs away from the lever 62 a spring 75, which was compressed during the retracting of the spindle 41, expands to actuate the sleeve 45 to the 95 left, as seen in Figure 4, for placing the center 41 within the adjacent end of the new unfinished work 36. The spring 75 is received in a suitable bore in the sleeve 45 and abuts on its one end with a shoulder 76 at the base of the bore and on its other end with a head 77 on tension adjusting screw 78.

The work, after being finished, is carried 100 downwardly in an arcuate path by the turret head 32 through an arcuate chamber 165 105

formed in the block or bracket 31 beneath the turret head 32, see Figures 4 and 5. Positioned on the upper surface of the block or bracket 31 and partially overlying the chamber 165 is a pair of strips 166 and 167 spaced from one another to form a passage 168 therebetween. The passage 168 is of a width slightly wider than the diameter of the body portion of the work but less than the diameter of the enlarged collar portion 169 on the work whereby the said strips 166 and 167 are adapted to engage the shoulder formed by the collar 169 and strip the work from the turret spindles 33 in the event the work tends to stick thereto.

The locking mechanism, above referred to, comprises a spring loaded plunger 79 slidably mounted in a lug 80 projecting from one side of the upright 40. The plunger 79 has on its outer end a roller 81 adapted to be engaged by the cam face 82 of spring loaded cam block 83 pivoted at 84 to an extending tail 85 of the post 58. The plunger 79, under the force of a spring 86, mounted thereabout, enters successive pockets 87 formed in the adjacent face of the turret 32. As the bar 55 moves to the left, as seen in Figure 3 and as above described, the cam face 82 engages the roller 81 for shifting the plunger 79 from the pocket 87 whereupon the turret is in condition to be indexed. Continued movement of the bar 55 commences the indexing of the turret whereupon the roller passes the cam block 83 under the influence of the spring 86 which holds the plunger against the said adjacent face of the turret 32 so that as soon as the next pocket is aligned therewith it is snapped in.

The work is fed into the grinding wheel by shifting the lower slide and the parts carried thereby toward the grinding wheel. This is accomplished automatically by the mechanism illustrated in Figures 7 to 10 inclusive. As there shown the adjusting screw 25 has secured to it at a point interiorly of the housing 27 a sliding block 88 by means of collars 89 and 90 flanking the ends thereof. The slide block is mounted in a bearing 91 extending inwardly from the side wall 50 of the housing 27 and the said slide block has pivoted to its opposite sides links 92, in turn, pivoted at the opposite ends to lugs 93 of bell crank lever 94 pivoted at 95 to the casing or housing 27. The depending arm 96 of the bell crank 94 has adjustably secured thereto a roller 97 mounted in a cam track 98 of cam 99. This cam 99 is secured to one end of worm shaft 100 having secured to it intermediate its ends the worm wheel 101 meshing with worm 102. The worm 102 projects through the casing 27 and is geared, as at 103, to a prime mover 104 secured to the bottom of the housing 27, as shown in Figure 1.

From the foregoing it will be noted that, due to the particular contour of cam groove

98, the screw 25 is first shifted toward the left at a rapid rate to take up the space between the work and grinding wheel. The screw is then further shifted toward the left at a comparatively slower rate to effect the desired and necessary stock removal from the work which is followed by a dwell in the movement of the parts to permit a complete rounding up of the work and a sparking out of the grinding wheel. This dwell is immediately followed by a rapid retraction of the screw so that the finished work piece may be replaced by an unfinished one.

To effect a timed sequential operation of the work supporting and indexing mechanism and the automatic feeding cycle there is mounted on the other end of the worm shaft 100 a second cam 105 having a cam face groove or track 106 which receives the roller 107 carried by a lever 108 intermediate its end. The lever 108 is pivoted at 109 to the casing 27 and has a pin and slot connection 110 at its other end with a valve stem 111. The valve stem 111 is integral with a spool type sliding valve 112 axially shiftable through a sleeve or bushing 113 for connecting a hydraulic medium under pressure with either conduits 114 or 115. The conduits 114 and 115 terminate at the opposite ends of a hydraulic cylinder 116 secured by any suitable means to the face of block or bracket 31 opposite to that along which the rod 55 moves. The cylinder 116 houses a piston 117 from which a rod 118 extends. The rod 118 is pivoted at 119 to one end of lever 120 pivoted intermediate its ends to the bracket 51 secured to the block 31. The other end of the lever 120 is pivoted at 121 to the sliding rod 55 and whereby movement of the piston 117 effects an opposite sliding movement of the rod 55.

The cam groove or track 106 bears a definite relation to the cam groove or track 98 so that the piston 117 is actuated to operate the work indexing and supporting centers at the time that the lower slide 20 is retracted whereby sufficient clearance is established between the work and grinding wheel to permit indexing thereof without endangering the size and finish of the work just ground.

In order to break the friction driving connection between the work and friction driving wheel at the time that the work is indexed from the unfinished station to the finished station, as well as from the finished station to the unloading point, a lost motion connection is provided between the upper and lower slides 20 and 21. This lost motion connection consists of a lug 122 receiving a link 123 attached to one end of spring 124 which has its other end secured as at 125 to the lower slide 20. From this it will be seen that a rearward pull on the upper slide 21 will, through the spring connection, carry with it the slide 20. This movement con-

- tinues until an adjustable stop in the nature of screw 126 carried by lug 127 standing upwardly from the bed 15 is encountered whereupon the slide 21 moves beyond the slide 20 tensioning the spring 124. Reverse shifting or a push on the slide 21 will take up the tension of the spring 124 whereupon the slides will move as a unit relative to the bed 15, as above described.
- 10 To maintain proper friction contact between the friction drive wheel 24 and the work 36 the wheel is of the yielding type, which consists of a spider 128 surrounding the spindle 23 having a series of pockets 129 therein receiving coiled springs 130. The coiled springs 130 abut on their other ends with driving lugs 131 entering suitable notches 132 formed in the ring 133 about which abrasive ring or wheel 24 is formed.
- 15 20 It will be understood that as the surface of the work is ground away the tendency will be for it to recede from the surface of the ring or wheel 24 and since the expansion of spring 124 is taken up initially no additional relative movement between slides 20 and 21 is provided. Therefore, as the said surface of the work recedes, the springs 130, which were initially placed under tension by displacing the surface of the wheel relative to
- 25 30 the axis of the spindle, expand to follow up the said receding surface.
- As was noted above, the work is loaded on the spindle at a point diametrically opposed to the grinding point. This work is automatically placed thereon from a suitable hopper 134 adjacent the grinding throat and exteriorly thereof. The hopper 134 forms no part of this invention, it being self-contained but tripped or operated in timed relation with the feeding and indexing mechanisms. The hopper 134 terminates in a feed slide 135 and a pusher 136 thereon for pushing the work from the slide 135 on the spindles 33 as they are successively aligned therewith. The 40 hopper mechanism is tripped or set in motion by a link 137 pivoted at 138 to a lever 139 on the end of a shaft 140 journaled in bearing 141 carried by a projecting ledge of block or bracket 31. The shaft 140 extends along the 45 front of the bed 15 and is journaled at its opposite end in bearings 142 of the housing 27. Secured to the shaft 140 interiorly of the housing 27 is a single tooth ratchet or plate 143 receiving the nose 144 of slidable pawl 145. This pawl 145 is adapted to be 50 slidably actuated through a bearing 146 integral with the housing 27 by means of a lever 147 pivoted at 148 to a portion of the housing 27. The lever 147 has a lug 149 extending therefrom and abuts with a spring 55 pressed plunger 150 of the casing or housing 27. The other end of the lever 147 has an upstanding lug 151 cooperating with a depending lug 152 of sliding pawl 145. Refer- 60 ring now to Figure 10, it will be noted that

the lever 147 has projecting from it a lug 153 adapted to cooperate with a lug 154 extending from the inner face of cam 99.

Rotation of the cam causes the lugs 153 and 154 to engage one another for actuating the lever 147 in a clockwise direction, as seen in Figure 10, about the axis of pivot 148 thereby tensioning the spring loaded plunger 150, and, through the interengagement of lugs 151 and 152, shifts the pawl 145 to the right, as seen in Figure 10. This movement of the pawl 145 rotates the shaft 140 and causes a tripping or actuation of the pusher 136 to place the work piece on the feed slide 135 on the turret spindles 33 next inclined to receive an unfinished work piece. As soon as the lugs 153 and 154 pass from under one another expansion of spring loaded pawl 150 retracts the shaft 140 and effects the deposition of a new work piece on the slide 135 ahead of the pusher 136 for the subsequent operation thereof.

What is claimed is:

1. In a grinding machine the combination of a bed, a grinding wheel rotatably mounted thereon, an opposed friction drive wheel spaced from the grinding wheel for providing a grinding throat therebetween, an indexible turret supporting work pieces in the grinding throat in simultaneous engagement with the grinding wheel and friction drive wheel, and additional supporting means in the grinding throat cooperating with the turret for supporting work pieces.

2. In a grinding machine the combination of a bed, a grinding wheel rotatably mounted thereon, an opposed friction drive wheel spaced from the grinding wheel for providing a grinding throat therebetween, an indexible turret supporting work pieces in the grinding throat in simultaneous engagement with the grinding wheel and friction drive wheel, additional supporting means in the grinding throat cooperating with the turret for supporting work pieces, and means effecting a relative feed between the work and grinding wheel to effect a stock removal from the work.

3. In a grinding machine the combination of a bed, a grinding wheel rotatably mounted thereon, an opposed friction drive wheel spaced from the grinding wheel for providing a grinding throat therebetween, an indexible turret supporting work pieces in the grinding throat in simultaneous engagement with the grinding wheel and friction drive wheel, additional supporting means in the grinding throat cooperating with the turret for supporting work pieces, means effecting a relative feed between the work and grinding wheel to effect a stock removal from the work, and means for automatically placing work pieces on the indexible turret.

4. In a grinding machine for grinding the exterior surface of work pieces concentric

- with a previously formed internal bore the combination of a bed, a grinding wheel rotatably mounted thereon, a friction drive wheel opposed to the grinding wheel and spaced therefrom to form a grinding throat, an indexible turret head having a plurality of spindles adapted to enter the bore in the work and carry said work from a loading position to the grinding throat, means for automatically placing the work on the turret spindle, and additional means cooperating with the turret spindles for supporting the work within the grinding throat in simultaneous engagement with the grinding wheel and friction drive wheel whereby the grinding wheel effects a stock removal from the work while it is being rotated by the friction drive wheel about an axis determined by the bore in the work.
5. In a grinding machine for grinding the exterior surface of work pieces concentric with a previously formed internal bore the combination of a bed, a grinding wheel rotatably mounted thereon, a friction drive wheel opposed to the grinding wheel and spaced therefrom to form a grinding throat, an indexible turret head having a plurality of spindles adapted to enter the bore in the work and carry said work from a loading position to the grinding throat, means for automatically placing the work on the turret spindle, additional means cooperating with the turret spindles for supporting the work within the grinding throat in simultaneous engagement with the grinding wheel and friction drive wheel whereby the grinding wheel effects a stock removal from the work while it is being rotated by the friction drive wheel about an axis determined by the bore in the work, and means for automatically stripping the work from the spindles at the conclusion of the grinding operation.
6. In a grinding machine for grinding the exterior surface of work pieces concentric with a previously formed internal bore the combination of a bed, a grinding wheel rotatably mounted thereon, a friction drive wheel opposed to the grinding wheel and spaced therefrom to form a grinding throat, an indexible turret head having a plurality of spindles adapted to enter the bore in the work and carry said work from a loading position to the grinding throat, means for automatically placing the work on the turret spindle, additional means cooperating with the turret spindles for supporting the work within the grinding throat in simultaneous engagement with the grinding wheel and friction drive wheel whereby the grinding wheel effects a stock removal from the work while it is being rotated by the friction drive wheel about an axis determined by the bore in the work, means for automatically stripping the work from the spindles at the conclusion of the grinding operation, and additional means for automatically indexing the turret to remove the finished work piece from the grinding throat and place an unfinished one therein.
7. In a grinding machine the combination of a bed, a grinding wheel rotatably carried by the bed, a slide carried by the bed and movable toward and from the grinding wheel, a rotatable friction drive wheel on the slide in opposition to the grinding wheel and forming a grinding throat therebetween, a turret carried by the slide indexible in a plane transversely of the grinding throat, a plurality of spindles on the turret adapted to enter the bore in the work, means for intermittently indexing the turret to successively place the work pieces within the grinding throat and remove same therefrom, and a retractable spindle opposed to the turret spindles when within a grinding throat and cooperating therewith to support the work piece for rotation.
8. In a grinding machine the combination of a bed, a grinding wheel rotatably carried by the bed, a slide carried by the bed and movable toward and from the grinding wheel, a rotatable friction drive wheel on the slide in opposition to the grinding wheel and forming a grinding throat therebetween, a turret carried by the slide indexible in a plane transversely of the grinding throat, a plurality of spindles on the turret adapted to enter the bore in the work, means for intermittently indexing the turret to successively place the work pieces within the grinding throat and remove same therefrom, a retractable spindle opposed to the turret spindles when within a grinding throat and cooperating therewith to support the work piece for rotation, means for actuating the slide toward the grinding wheel to effect a feed between the work and grinding wheel and a stock removal from the work, means for retracting the tailstock spindle at the conclusion of the grinding operation, and means synchronizing the shifting of the slide toward and from the grinding wheel and the indexing of the turret and retraction of the tailstock spindle.
9. In an automatic grinding machine for grinding the exterior surface of hollow work pieces concentric with the axis of the bore the combination of a bed, a pair of opposed grinding and friction drive wheels carried thereby and forming a grinding throat therebetween, a slide for one of the wheels whereby it may be actuated toward and from the other wheel, indexible means having work supports thereon operable in a plane transversely of the grinding throat to place work pieces in and remove same from the said throat, additional support means carried by the slide cooperating with the indexible support, means for retracting the additional support at the conclusion of the grinding opera-

- abrasive wheel, yielding means for terminal-
ly engaging the work while adjacent the
wheel, and means automatically retracting
the terminal means prior to the indexing of
5 the turret.
17. In a machine tool organization the
combination of a bed, an abrasive wheel
rotatably mounted thereon, an indexable car-
rier for positioning work pieces adjacent the
10 abrasive wheel, yielding means for terminal-
ly engaging the work while adjacent the
wheel, means automatically retracting the
terminal means prior to the indexing of the
15 turret, and friction drive means for rotat-
ing the work while supported by the termi-
nal engaging means. 80
18. In a machine tool organization the
combination of a bed, an abrasive wheel
rotatably mounted thereon, indexable means
20 for positioning work pieces adjacent the
operative face of the wheel, means terminal-
ly engaging the work adjacent the wheel, and
friction drive means for rotating the work
while in contact with the wheel. 85
- 25 19. In a machine tool organization the
combination of a bed, an abrasive wheel
rotatably mounted thereon, indexable means
for positioning work pieces adjacent the
operative face of the wheel, means terminal-
30 ly engaging the work adjacent the wheel,
friction drive means for rotating the work
while in contact with the wheel, means auto-
matically separating the terminal engaging
means prior to the indexing of the turret, and
35 means discharging the work from the turret. 90
20. In a machine tool organization the
combination of a bed, an abrasive wheel
rotatably mounted thereon, a turret support-
ing a plurality of work pieces indexable to
40 position successive pieces in operative rela-
tion with the wheel, terminal means sup-
porting the work adjacent the wheel includ-
ing a center yieldably shifted toward the
work, and friction drive means for rotating
45 the work while terminally supported in con-
tact with the wheel. 105
21. In a machine tool organization the
combination of a bed, an abrasive wheel
rotatably mounted thereon, a turret support-
ing a plurality of work pieces indexable to
50 position successive pieces in operative rela-
tion with the wheel, terminal means sup-
porting the work adjacent the wheel includ-
ing a center yieldably shifted toward the
work, friction drive means for rotating the
55 work while terminally supported in contact
with the wheel, and means automatically
retracting the center against the yielding
resistance of the center projecting yielding
means. 110
22. In a machine tool organization the
combination of a bed, an abrasive wheel
rotatably mounted thereon, a turret support-
ing a plurality of work pieces indexable to
60 position successive pieces in operative rela-
tion with the wheel, terminal means support-
ing the work adjacent the wheel including a
center yieldably shifted toward the work,
friction drive means for rotating the work
65 while terminally supported in contact with
the wheel, means automatically retracting the
center against the yielding resistance of the
center projecting yielding means, and means
automatically placing work pieces on the
70 turret. 75
- In testimony whereof I affix my signature.
FREDERICK J. THELER.
